Inventor

George McD. Johns

By J.R. Cornwall, Atty.

UNITED STATES PATENT OFFICE.

GEORGE McD. JOHNS, OF ST. LOUIS, MISSOURI, ASSIGNOR TO W. N. MATTHEWS AND BROTHER, INC., OF ST. LOUIS, MISSOURI, A CORPORATION OF NEW MEXICO.

ATOMIZER.

1,330,448.

Specification of Letters Patent. Patented Feb. 10, 1920.

Application filed February 20, 1919. Serial No. 278,132.

To all whom it may concern:

Be it known that I, GEORGE McD. JOHNS, a citizen of the United States, residing at St. Louis, Missouri, have invented a certain 5 new and useful Improvement in Atomizers, of which the following is a full, clear, and exact description, such as will enable others skilled in the art to which it appertains to make and use the same, reference being had 10 to the accompanying drawings, forming part of this specification, in which—

Figure 1 is a top plan view of my improved atomizer.

Fig. 2 is a side elevational view of my 15 improved atomizer partly in vertical section.

Fig. 3 is a cross-sectional view through the cap casting.

Fig. 4 is a detailed view of the handle 20 arrangement.

Fig. 5 is a detailed view of the container housing.

This invention relates to a new and useful improvement in atomizers of that type 25 designed partly for use in spraying paint, insecticides, etc., and which is commonly known as a paint gun or spraying gun. The object of my invention is to simplify the construction of atomizers of the character described, cheapen the construction thereof, and make such devices efficient, and enable dismantling for the purposes of 30 cleaning, repairing or renewing the parts.

In the drawings, 1 indicates a container 35 preferably in the form of a well-known type of fruit jar and which is designed to receive the paint, spray, insecticide, spraying compound or other material to be used.

2 indicates the housing for the container 40 preferably made in the form of an open ended metal cylinder, around and within the upper edge of which are a series of centering or cushioning tongues, 3 for holding the housing in position on the container. 45 By the use of a metal housing, the glass container is preserved against breakage from knocks or jars received in service.

The upper side of the container 1 is provided with the usual screw thread 1^a for 50 engagement with the threaded flange 4^a of a casting 4. At the base of this flange 4^a a

packing ring or gasket 5 is preferably employed—not so much for the purpose of making an air tight fit, but to prevent accidental leakage of the liquid contents of the 55 container at this point, as there is a vent opening 4^b for permitting the entrance of air above the surface of the liquid contents.

Casting 4 is preferably made in a metal mold so that the openings therein can be 60 formed by metal cores.

6 indicates a pipe preferably screwed into the casting 4 and extending down into the container 1 and terminating near the bottom thereof. The opening in pipe 6 communicates with a duct 7 in the casting, the other end of which is threaded or tapped as shown in Fig. 2 to receive a nipple 8, the end of said nipple being tapered as shown.

9 indicates a duct in the casting 4, communicating with a source of compressed air supply and controlled in a manner herein-after described. The exit end of duct 9 terminates at one side of the nipple 8 as shown in Fig. 2.

10 indicates a nozzle member whose inner end is formed with a cylindrical bore to receive the projecting end of casting 4, which at this point is also made cylindrical. The interior bore of nozzle 10 is reduced by 75 a shoulder 10^a and thence formed tapering, into or through which tapering bore projects the nipple 8. The outer surface of nozzle 10 is preferably tapered or formed conical as shown.

10^b indicates lugs extending outwardly from the inner end of the nozzle and through which passes a butterfly clamping nut 11. In order to permit these lugs to have movement to and from their clamping position, they are partly severed from the sleeve constituting the nozzle by a saw kerf 10^c. By this arrangement, the nozzle may be adjusted inwardly, outwardly and circumferentially on the cylindrical portion 80 of casting 4, and locked into its adjusted position by turning off the butterfly nut. There are no screw threads employed in the mounting of the nozzle on the casting, and this is deemed an advantage as the parts 85 are not liable to stick and thereby prevent adjustment, when in dis-use for any length 90 95 100

of time, and which dis-use might occasion a drying of the paint or liquid upon or around the nozzle.

The duct 9 referred to communicates 5 with a chamber in which is arranged a ball valve 12, said valve being held to its seat by means of a spring 13.

14 indicates a valve operating button whose shank or stem passes through the casting 4 and terminates above the ball valve 12. In order to prevent accidental 10 displacement of this valve operating button, the inner end of the stem thereof is preferably upset or formed with a head as shown in Fig. 2. A washer 15 is preferably arranged under the head of the valve operating button.

In order to secure the spring 13 in place, 20 a pipe 16 is screwed into the lower threaded end of the valve chamber, the said pipe having its lower end threaded to receive a nipple on a nut 17.

18 indicates a handle of wood, fiber, or some suitable material, said handle being 25 preferably cylindrical in cross-section, and having its upper end notched as indicated at 18^a, in Fig. 4, so as to receive a projection on the casting 4 whereby the handle is held against rotation. The nut 17 impacts 30 against a washer 19 arranged in a notch or recess in the lower end of the handle and the handle is thus clamped in position on the pipe 16 by a nut 17.

In order to effect a convenient and quickly 35 operated connection between the source of air supply and the pipe 16, and to enable free manipulation of the atomizer, I employ preferably a rubber tube 20 leading from the source of air supply into the end of 40 which is screwed an angularly arranged nipple 21, having a threaded flange 22 forming a seat for a rubber nipple-engaging washer 23 which may be of any well-known construction and shape, said rubber washer 45 being held in position by a threaded cap 24.

The operation of the device is obvious from the foregoing description. The paint or other liquid ingredient to be sprayed is placed in the container and the parts assembled—the pipe 20 being connected to some 50 suitable source of air supply. In practice, I have found that a pressure of from 18 to 25 pounds gives satisfactory results. The pressure of the air from the source of supply, assisted by the spring 13, tends to close 55 the ball valve 12 and when the valve 12 is closed, there is no siphoning action, and, consequently no spraying of the paint or contents of the container 1. When the valve 60 operating button is pressed and air permitted to flow through the duct 9 and out through the nozzle, it will draw the contents from the container up through the pipe 6, and out of the nozzle 8, and cause the

liquid contents so drawn through the nipple, 65 to be spread out or sprayed, the air breaking the stream issuing from the nipple into small particles or divisions.

What I claim is:

1. An atomizer of the character described 70 comprising a container, a housing for said container, and cushioning tongues on said housing for frictionally engaging said container.

2. An atomizer of the character described 75 comprising a glass container, a metal housing inclosing said container, cushioning devices interposed between said container and said housing, a cap casting detachably mounted on said container and provided 80 with ducts or passages, a nipple arranged at the extremity of one of said ducts, a nozzle around said nipple and in communication with the other of said ducts, and means for controlling air pressure through the last 85 mentioned duct.

3. An atomizer comprising a container and a detachable cap, said cap being in the form of a casting, having ducts therein, a nozzle arranged on said casting and in communication with one of said ducts, said nozzle having perforated lugs or ears partly severed therefrom, and a clamping means 90 co-operating with said lugs or ears for securing the nozzle in an adjusted position on 95 said casting.

4. An atomizer comprising a container, and a cap casting provided with ducts, one of said ducts being in communication with the interior of the container and terminating 100 in a nipple, and the other of said ducts communicating with the interior of a nozzle surrounding said nipple, a nozzle having yielding lugs or ears, and a clamping means co-operating with said lugs or ears for securing 105 said nozzle in relation to said nipple, and means for controlling the supply of air pressure to said nozzle.

5. In an atomizer of the character described, the combination of a container and 110 a cap casting detachably mounted thereon, a manually operated valve arranged in said casting, a handle secured to the casting, and means for locking the handle against rotary movement on the casting. 115

6. In an atomizer, the combination of a container and its cap casting, said casting being provided with a duct for the passage 120 of compressed air, a manipulative valve arranged in said duct, a pipe secured to the casting and terminating in a nipple for connection to a source of air supply, a handle arranged upon said pipe, and means upon said nipple for engaging said pipe and holding said handle in position. 125

7. In an atomizer, the combination of a container and a cap casting, the latter being provided with an air duct for the passage of

compressed air, a manipulative valve arranged in said duct, a pipe screwed into said casting and communicating with said duct, a handle arranged upon said pipe and provided with means for engaging the casting to prevent rotation of said handle, a nipple threaded upon said pipe for engaging the handle and holding the same in position, and

a supply pipe leading from the source of compressed air supply, said supply pipe having means for quick attachment and detachment from said nipple.

In testimony whereof I hereunto affix my signature this 17th day of February 1919.

GEO. McD. JOHNS.
